CLAIM

The ornamental design for a light fixture, as shown and described.

DESCRIPTION

FIG. 1 is a bottom perspective view of an embodiment of a light fixture.

FIG. 2 is a bottom plan view of the light fixture of FIG. 1.

FIG. 3 is a top plan view of the light fixture of FIG. 1.

FIG. 4 is a front elevation view of the light fixture of FIG. 1, the rear elevation view being a mirror image of the front view.

FIG. 5 is a right side elevation view of the light fixture of FIG. 1, the left side elevation view being a mirror image of the right side view.

FIG. 6 is a bottom perspective view of another embodiment of a light fixture, it being understood that the top plan view is identical to the view shown in FIG. 3, that the front and rear elevation views of the light fixture are identical to the view shown in FIG. 4, and that the right and left side elevation views of the light fixture are identical to the view shown in FIG. 5.

FIG. 7 is a bottom plan view of the light fixture of FIG. 6.

FIG. 8 is a bottom perspective view of another embodiment of a light fixture, it being understood that the top plan view is identical to the view shown in FIG. 3, that the front and rear elevation views of the light fixture are identical to the view shown in FIG. 4, and that the right and left side elevation views of the light fixture are identical to the view shown in FIG. 5.

FIG. 9 is a bottom plan view of the light fixture of FIG. 8.

FIG. 10 is a bottom perspective view of another embodiment of a light fixture, it being understood that the top plan view is

identical to the view shown in FIG. 3, that the front and rear elevation views of the light fixture are identical to the view shown in FIG. 4, and that the right and left side elevation views of the light fixture are identical to the view shown in FIG. 5.

FIG. 11 is a bottom plan view of the light fixture of FIG. 10. FIG. 12 is a bottom perspective view of another embodiment of a light fixture, it being understood that the top plan view is identical to the view shown in FIG. 3, that the front and rear elevation views of the light fixture are identical to the view shown in FIG. 4, and that the right and left side elevation views of the light fixture are identical to the view shown in FIG. 5.

FIG. 13 is a bottom plan view of the light fixture of FIG. 12. FIG. 14 is a bottom perspective view of another embodiment of a light fixture, it being understood that the top plan view is identical to the view shown in FIG. 3, that the front and rear elevation views of the light fixture are identical to the view shown in FIG. 4, and that the right and left side elevation views of the light fixture are identical to the view shown in FIG. 5.

FIG. 15 is a bottom plan view of the light fixture of FIG. 14. FIG. 16 is a bottom perspective view of another embodiment of a light fixture, it being understood that the top plan view is identical to the view shown in FIG. 3, that the front and rear elevation views of the light fixture are identical to the view shown in FIG. 4, and that the right and left side elevation views of the light fixture are identical to the view shown in FIG. 5.

FIG. 17 is a bottom plan view of the light fixture of FIG. 16. FIG. 18 is a bottom perspective view of another embodiment of a light fixture, it being understood that the top plan view is identical to the view shown in FIG. 3, that the front and rear elevation views of the light fixture are identical to the view shown in FIG. 4, and that the right and left side elevation views of the light fixture are identical to the view shown in FIG. 5.

FIG. 19 is a bottom plan view of the light fixture of FIG. 18. FIG. 20 is a bottom perspective view of another embodiment of a light fixture, it being understood that the top plan view is identical to the view shown in FIG. 3, that the front and rear elevation views of the light fixture are identical to the view shown in FIG. 4, and that the right and left side elevation views of the light fixture are identical to the view shown in FIG. 5.

FIG. 21 is a bottom plan view of the light fixture of FIG. 20. FIG. 22 is a bottom perspective view of another embodiment of a light fixture, it being understood that the top plan view is identical to the view shown in FIG. 3, that the front and rear elevation views of the light fixture are identical to the view shown in FIG. 4, and that the right and left side elevation views of the light fixture are identical to the view shown in FIG. 5.

FIG. 23 is a bottom plan view of the light fixture of FIG. 22.

FIG. 24 is a bottom perspective view of another embodiment of a light fixture, it being understood that the top plan view is identical to the view shown in FIG. 3, that the front and rear elevation views of the light fixture are identical to the view shown in FIG. 4, and that the right and left side elevation views of the light fixture are identical to the view shown in FIG. 5.

FIG. 25 is a bottom plan view of the light fixture of FIG. 24. FIG. 26 is a bottom perspective view of another embodiment of a light fixture, it being understood that the top plan view is

identical to the view shown in FIG. 3, that the front and rear elevation views of the light fixture are identical to the view shown in FIG. 4, and that the right and left side elevation views of the light fixture are identical to the view shown in FIG. 5.

FIG. 27 is a bottom plan view of the light fixture of FIG. 26. FIG. 28 is a bottom perspective view of another embodiment of a light fixture, it being understood that the top plan view is identical to the view shown in FIG. 3, that the front and rear elevation views of the light fixture are identical to the view shown in FIG. 4, and that the right and left side elevation views of the light fixture are identical to the view shown in FIG. 5.

FIG. 29 is a bottom plan view of the light fixture of FIG. 28. FIG. 30 is a bottom perspective view of another embodiment of a light fixture, it being understood that the top plan view is identical to the view shown in FIG. 3, that the front and rear elevation views of the light fixture are identical to the view shown in FIG. 4, and that the right and left side elevation views of the light fixture are identical to the view shown in FIG. 5.

FIG. 31 is a bottom plan view of the light fixture of FIG. 30. FIG. 32 is a bottom perspective view of another embodiment of a light fixture, it being understood that the top plan view is identical to the view shown in FIG. 3, that the front and rear elevation views of the light fixture are identical to the view shown in FIG. 4, and that the right and left side elevation views of the light fixture are identical to the view shown in FIG. 5.

FIG. 33 is a bottom plan view of the light fixture of FIG. 32. FIG. 34 is a bottom perspective view of another embodiment of a light fixture, it being understood that the top plan view is identical to the view shown in FIG. 3, that the front and rear elevation views of the light fixture are identical to the view shown in FIG. 4, and that the right and left side elevation views of the light fixture are identical to the view shown in FIG. 5; and,

FIG. 35 is a bottom plan view of the light fixture of FIG. 34. Portions or features of the light fixture not shown in the drawings form no part of the claimed design. The broken lines in the drawings form no part of the claimed design.
